UNITED STATES PATENT OFFICE.

JOHN P. BADENHAUSEN, OF PHILADELPHIA, PENNSYLVANIA.

BOILER.

1,374,484.

Specification of Letters Patent. Patented Apr. 12, 1921.

Application filed March 18, 1918. Serial No. 85,124.

To all whom it may concern:

Be it known that I, JOHN P. BADENHAUSEN, a citizen of the United States, residing at Philadelphia, in the county of 5 Philadelphia and State of Pennsylvania, have invented new and useful Improvements in Boilers, of which the following is a specification.

This invention relates to boilers and has 10 for an object to provide a boiler with means for directing and regulating the flow and action of the gases of combustion upon the water heating surfaces of said boiler.

Another object of the invention is to provide 15 a boiler with baffle plates which are designed to direct the passage of the gases of combustion in a manner to obtain the maximum heat values thereof upon the water heating surfaces of the boiler.

20 To this end, the invention comprises a boiler having one or more transverse mud drums, water drums and steam-and-water drums which are connected by banks of tubes, and a further object is to provide a 25 boiler of this class with baffle plates so arranged and disposed as to break up the currents of the gases of combustion and bring the particles of this gas into more intimate contact with the boiler heating surfaces than 30 has hitherto been obtainable, thereby increasing the efficiency and capacity of the boiler.

Other objects of the invention will be in 35 part obvious and in part pointed out hereafter.

The invention accordingly consists in the features of construction, combination and arrangement of parts, as will be hereinafter more fully described, illustrated in the accompanying drawings and pointed out in the claims hereunto appended.

In the drawings,

Figure 1 illustrates a vertical longitudinal, sectional view through a boiler, showing 45 the application of the present invention,

Fig. 2 is a similar view disclosing a slightly modified form of boiler,

Fig. 3 is a detail transverse sectional view, on the line 3—3 of Fig. 2, illustrating the 50 means for inserting or removing the baffle plates.

Like characters of reference denote similar parts throughout all of the views of the drawings.

55 Referring more particularly to the drawings, the type of boilers shown consists, in both instances of a plurality of transversely

disposed drums connected by angularly extending banks of tubes, the drums and tubes comprising the water circulating system of 60 the boiler. The lower or mud drum 1, is connected with a superimposed water drum 2 by means of an inclined bank of tubes 3, the tubes having been designated *per se* by the letter *a*, and said bank of tubes 3 being 65 hereinafter referred to as the "first bank" of tubes. A steam and water drum 4 is tangentially located with respect to the water drum 2, and is connected with the latter by means of a second bank of tubes 5, each tube 70 being designated by the letter *b*, such tubes being mentioned, in the following description, as the "second bank" of tubes. A third bank of tubes 6, connects the steam and water drum 4 with the mud drum 1, each 75 tube having been suitably designated by the letter *c*, and said bank of tubes 6 being, for purposes of description, referred to hereinafter as the "third bank" of tubes. The fire box 9 contains the usual grates 10, the fire 80 arch 11, (if one be necessary) and a bridge wall 12, but it is to be understood, however, that these parts may all be modified to suit the fuel to be burned, and that any other form of grate or stoker, oil or gas burner, 85 sawdust or shaving feeder may also be used without, in any manner, affecting the operation of the invention.

The other usual attachments to a boiler are provided, and consist of a housing or 90 setting 13, having a front wall 14, a rear wall 15 and a damper box 16 through which the gases of combustion leave the boiler on the way to the usual stack, not shown. Suitable openings 17, 18, 19, 20, 21, 22, 23, 95 24 and 25, are formed in the housing or setting 13, and are so placed as to enable a person to enter the several spaces between the boiler tube banks and the setting walls, and also to permit the insertion of a steam 100 lance in order to blow soot from the surfaces of the tubes. A "blow off" pipe 26 terminates in a blow off valve 27, the latter being illustrated diagrammatically. The usual water column and gage glass 27' is 105 connected with the drum, as shown. In Fig. 1 the housing or setting is provided with a top 28 of any suitable formation. The drum 4 is provided with a standard design of steam nozzle 29; a boiler feed pipe 110 30 also enters the drum 4 in substantially the manner indicated.

It is to be observed that, as illustrated in Figs. 1 and 2, the tube banks 3 and 5 are

oppositely inclined to the horizontal and form an acute angle which is superimposed over a horizontal line through the vertex of said angle, but the invention applies with equal force to an arrangement in which there might be other than an acute angle and in which the tube bank 5 might be horizontally disposed.

In accordance with modern scientific investigation, the efficiency and capacity of a boiler depend principally upon the speed of travel of the hot gases over the outside of the heating surface, and the speed with which the boiler water travels along the inside of the heating surface. (See Bulletin No. 18, Bureau of Mines, "The Transmission of Heat into Steam Boilers," pages 24, 79, 118 to 122, and 155 to 161. Also see Bulletin No. 325, U. S. Geological Survey, "A Study of 400 Steaming Tests," pages 109, 110, 113 to 118, 129 to 132.) By my invention I obtain the desired speed of gas travel as well as the length of the gas courses, by use of the baffle arrangement herein disclosed.

It is also well known to those skilled in the art that when a boiler is fired with coal or other fuel containing a high content of volatile matter and a low content of fixed carbon, the most efficient results are obtained by so arranging the passage of the gases of combustion that they will flow along practically parallel to the boiler tube surface, particularly over the fire, whereas, when the coal or fuel contains a high content of fixed carbon and a low content of volatile matter the best results are obtainable when the gases circulate across the heating surfaces of the boiler at approximately right angles to the axis of a tube, hence to produce a boiler of the highest general efficiency, means must be provided to compel the gases, during their course from the furnace to the breeching, to travel first in one of these ways, then the other, and these methods will be herein-after referred to as "parallel-flow" and "cross flow" of the gases.

In my invention I obtain these desired results, that is, a combined parallel flow and cross flow of the gases along the heating surfaces of the boiler, as will be presently shown. On top of the lower part of the first tube bank 3, there is provided a baffle A, the length of which depends upon the fuel and draft conditions; above the baffle A there is provided an approximately vertical baffle B, which may or may not, as conditions require, have an offset C, and this baffle at its lower part is supported by one or more channel irons or the equivalent, as has been indicated by the numerals 31 and 32, and the upper portion B' of the baffle B, is supported on part of the tubes 5 of the second bank. At the top of the baffle B' there is provided another baffle D, which is horizontally dis-

posed upon the bank of tubes 5 and extends forwardly from the baffle B' to the forward wall of the housing. Located rearwardly of the baffle B, there is provided another baffle E, supported by angle irons or the like 70 33. In the third bank of tubes 6 there is formed a baffle F, which extends parallel to the tubes 6 and is centrally located in the latter. Angle irons 34 secured to the housing of the boiler retain the baffle F in its 75 fixed position. Due to the baffles thus arranged, the gases of combustion arising from the fire box 9 are caused to travel as shown by the arrows e, f, g, h, i, j, k, l, m, n, p, q, and r, in which the parallel and cross flows, 80 and the frequent change from one to the other, are made evident. A baffle G may be inserted in the forward end of the second bank 5, whenever an occasion demands such construction, or if the size of the boiler warrants such an addition, the operation and action of the baffle G will be obvious. It will be observed that the gas passages or ports between the baffle G and the baffles A, C and D are smaller in area than the gas 85 passages or ports provided between the arch 11 and the drum and baffles 1 and A, and also that the gas passages or ports provided between the baffle F and the baffle, drum and wall E, 1 and 15 respectively are smaller in 90 area than the gas passages or ports provided between the drum 4 and the baffles B and B'. In Fig. 2, which represents one of the preferred forms of my boiler, the construction shown is identical to that illustrated in Fig. 100 1, with the exception of adding a receiving drum or receptacle 35, connected by tubes 36 to the drum 4. The top or covering 37 extends parallel to the tubes 36 and access doors 38 and 39 are formed adjacent said 105 tubes 36 for the same purpose previously mentioned in connection with the door 17 to 25 inclusive. A steam outlet 40 is connected with the drum 35, as is a water column and gage glass 41, the latter also having connection with the water drum 2. The operation and construction of the steam receiving drum 35 and its co-operating tubes 36 has been fully set forth in my co-pending patent application bearing Serial No. 81977, filed 110 March 3rd, 1916.

The only way in which the gases of combustion travel in Fig. 2 differently from that mentioned in Fig. 1, is that when the gases emerge from the top of the bank 5, as shown 115 120 by the arrow j, part of said gases travel as shown by the arrow k while another part continues up to the tubes 36, first cross flowing in among these tubes, then parallel flowing along them, as shown by the arrows 125 s. The gases leave the pipes 36 with a "cross-flow," as indicated by the arrows t, and the two streams of gas unite and flow as shown by the arrows l. Since, in the design of most water tube boilers it is neces-

sary to insert the baffles while the boiler is in course of erection, and impossible to alter or repair the baffles later, after the erection of the boiler, except by tearing down portions of the boiler housing or setting walls, I have, as part of my invention, arranged and constructed the housing so that any baffle can be readily and conveniently removed, replaced or repaired without tearing down or damaging any part of said boiler housing. For illustration, baffle A, can be reached through the doors 17 and 18; baffle E can be reached through the doors 17 and 19 and the part of the baffle B between the banks 3 and 5 can be reached through the doors 18, 17 and 19. The upper part of the baffle B or the baffle B' is built after the tubes 5 are in place, and consists of fire brick and high temperature cement, so that by passing through the door 38 or 39 a workman can remove or repair this part of the baffle. To enable the baffles C to be removed or repaired, there is provided in the side wall of the housing, openings N and M, as shown in Figs. 1 and 2, and detailed in Fig. 3, said openings being closed by the removable caps 37'. Similar openings are provided at 38' and 39' in the housing for handling the baffle F. Also, baffle offset in the baffle B (if used) can be handled through the opening M. As the baffles A, D, F, and G are made or formed of tile blocks, all that is necessary for removing these blocks is to slide them one by one along the tubes to their respective openings, and then withdraw them from the housing, which may be easily accomplished by an operator working from the spaces within the setting between the tube banks, reached by the doors 17, 18 and 19.

It is now known that to obtain the best operating results it is necessary to adjust the baffle opening in water tube boilers to meet the requirements of the particular kind of fuel being used, the boiler rating desired and the draft conditions existing. Previous designs of baffles have not permitted of such an adjustment except at great expense and delay, but in this invention I contemplate making such necessary adjustments easily and quickly and at practically no expense. Accordingly the lengthening or shortening of the baffles A, F, D, and G; by removing or adding one or more rows of tiles in the manner above described, will result in the gas openings, being widened or narrowed to suit any of the conditions confronted.

From the foregoing description, it will be evident that the following functions are accomplished. Firstly, so lengthening the path of gas travel as to produce the highest efficiency in the boiler construction. Secondly, by repeatedly alternating the gas travel from parallel-flow to cross flow and vice-versa, thus constantly breaking up the

gas currents so as to bring each particle of gas into intimate contact with the boiler tube surface as is necessary in order to extract the maximum quantity of heat from the gas. Thirdly, by contracting the area of the gas passages to the degree necessary to give the greatest practicable operating efficiency and fourthly, by providing simple and efficient means of adjusting the area of the gas passages to give the best results for any given set of conditions.

In the foregoing description, I have illustrated and explained the baffle location as found by practice to suit the majority of cases, however, it should be understood that I do not limit myself to the exact position. Thus baffle F is shown in the center of the tube bank 6, but the latter may be moved forwardly or backwardly from the center if the occasion should present itself. The baffle C resting on the bottom tube of the bank 5, and the baffle D resting on the third tube from the top of the bank 5, may be changed in position according to the size of the boiler and number of tubes in a bank, by placing the baffles C and D on any other desired row of tubes from that shown. The baffle E has been shown and described as consisting of one horizontal section and an inclined section, but this baffle may be formed of a single horizontal section or a single angularly disposed section. In the disclosure are shown drums connected by curved tubes, but the particular form of construction is not essential and the invention is intended to apply to any equivalent structure, such as for example wherein a header or water-leg may be used in lieu of drums and straight tubes utilized in lieu of curved tubes, as well as comprehending all such possible changes of baffle location or material, or shape of drums or water and steam receptacles or tubes, as I may elect within the scope of the claims hereunto appended.

Having described the present invention, what is claimed as new and patentable is:

1. A water tube boiler having a transverse mud drum, a transverse water drum, a transverse steam-and-water drum, a steam receiving drum, tubes connecting said mud drum with the water drum, tubes connecting said water drum with the steam-and-water drum, tubes connecting the steam-and-water drum with said mud drum, a plurality of steam conveying and superheating tubes connecting said steam-and-water drum with the receiving drum, and baffle means including a baffle extending forwardly over the top tubes of said first mentioned tubes, a baffle extending upwardly and forwardly therefrom into said second mentioned tubes, said last mentioned baffle provided with a rearwardly extending baffle, and a baffle in said third mentioned tubes extending from said steam-and-water drum downwardly

toward said mud drum, whereby the gases of combustion pass downwardly along the forward part of said third mentioned tubes, transversely of the latter at the lower end 5 thereof, upwardly along the rear part of said tubes and with a cross flow transversely of the upper part of the rear tubes thereof, said baffles arranged to provide therebetween contracted gas passages for effecting increased efficiency of operation and to change the course of the flow of the hot gases for the intimate contact of said hot gases with the tubes of said boiler.

2. A boiler comprising a mud drum, a 15 water drum and a steam-and-water drum, tubes connecting said mud drum with the water drum, tubes connecting said water drum with the steam-and-water drum, tubes connecting the latter drum with said mud drum, and baffle means including a baffle extending forwardly over the top tubes of said first mentioned tubes, a baffle extending upwardly and forwardly therefrom into said second mentioned tubes substantially at 20 right angles to the axis of the tubes, a branch baffle extending forwardly from the upper end of said upwardly extending baffle, a baffle extending from a point adjacent to the water drum rearwardly along the bottom 25 tubes of the tubes connecting the water and steam-and-water drums and substantially parallel to and at a lower level than the forwardly extending baffle, a baffle in said third mentioned tubes extending from said steam-and-water drum downwardly toward said mud drum, said baffles arranged to provide therebetween contracted gas passages for 30 effecting increased efficiency of operation and to change the course of the flow of the hot gases for the intimate contact of said hot gases with the tubes of said boiler.

3. A boiler comprising, in combination, transverse mud, water, and steam-and-water drums, a transverse steam receiving drum, 45 a bank of tubes connecting the mud drum with the water drum, a second bank of tubes connecting the water drum with the steam-and-water drum, a third bank of tubes connecting the latter drum with said mud drum, a plurality of steam conveying and super-heating tubes connected with said steam-and-water drum and with the receiving drum and baffle means including a baffle extending forwardly over the top tubes of 50 said first mentioned tubes, a baffle extending upwardly and forwardly therefrom into said second mentioned tubes substantially at right angles to the axis of said tubes, a branch baffle extending forwardly from the 55 top of the upwardly extending baffle and a baffle extending from a point adjacent to the water drum rearwardly along the lower tubes of the second bank substantially parallel to and at a lower level than said branch 60 baffle, a baffle in said third mentioned tubes 35

extending from said steam-and-water drum downwardly toward said mud drum, said baffles arranged to provide therebetween contracted gas passages for effecting increased efficiency of operation and to change the course of the flow of the hot gases for the intimate contact of said hot gases with the tubes of said boiler.

4. A water tube boiler comprising, in combination, transversely disposed mud, water, and steam-and-water drums, a bank of tubes connecting the mud drum with the water drum, a second bank of tubes connecting the water drum with the steam-and-water drum, a third bank of tubes connecting the latter drum with said mud drum, a baffle in said third mentioned tubes extending from said steam-and-water drum downwardly toward said mud drum, a forwardly extending gas directing baffle disposed over the top tubes of the first mentioned bank of tubes, a substantially vertical baffle extending upwardly from the said second mentioned baffle into the second bank of tubes, a branch baffle extending forwardly from the upper part of the third mentioned baffle and extending over the lower tubes of the second mentioned bank of tubes, an upwardly and forwardly extending baffle leading from said fourth mentioned baffle 90 through said second mentioned bank of tubes and a baffle extending rearwardly from said water drum over the lower tubes of said second mentioned bank of tubes providing ports of different sizes between said 95 last mentioned baffle and said second, fourth and fifth mentioned baffles to effect increased efficiency of operation and to change the course of the flow of the hot gases for the 100 intimate contact of said hot gases with the 105 tubes of said boiler.

5. A water tube boiler, comprising in combination, a mud drum, a water drum, a steam-and-water drum, a bank of tubes connecting the mud drum with the water drum, a second bank of tubes connecting said water drum with said steam-and-water drum, a third bank of tubes connecting the latter with said mud drum, a baffle in said third mentioned tubes extending from said 110 steam-and-water drum downwardly toward said mud drum, a baffle extending from said mud drum over the top tubes of the first mentioned bank of tubes, a substantially vertical baffle extending upwardly 115 from said second mentioned baffle into said second mentioned bank of tubes, a branch extending rearwardly from said third mentioned baffle between the first and second mentioned tube banks and with the end 120 thereof adjacent the third mentioned bank of tubes, another branch baffle extending forwardly from the top of the third mentioned baffle and located within the second 125 mentioned bank of tubes, a baffle extending 130

rearwardly from the water drum along the lower tubes of the second mentioned bank of tubes and providing ports of different sizes between said last mentioned baffle and said 5 second, third and fifth mentioned baffles to effect increased efficiency of operation and to

change the course of the flow of the hot gases for the intimate contact of said hot gases with the tubes of said boiler.

In testimony whereof I affix my signature. 10

JOHN P. BADENHAUSEN.
